(57) **CLAIM**

The ornamental design for a scoreboard in the form of a pennant, as shown and described.

DESCRIPTION

FIG. 1 is a front elevational view of a scoreboard in the form of a pennant;

FIG. 2 is a top plan view thereof;

FIG. 3 is a bottom plan view thereof;

FIG. 4 is a side elevational view thereof; and,

FIG. 5 is another side elevational view thereof.

The broken lines environment is for illustrative purpose only and forms no part of the claimed design.
